UNITED STATES PATENT OFFICE.

JAMES THOMAS PARKER, OF HATTIESBURG, MISSISSIPPI.

AUGER-BIT.

No. 850,177.

Specification of Letters Patent.

Patented April 16, 1907.

Application filed October 20, 1906. Serial No. 339,875.

To all whom it may concern:

Be it known that I, JAMES THOMAS PARKER, a citizen of the United States, residing at Hattiesburg, in the county of Perry and State of Mississippi, have invented a new and useful 5 Auger-Bit, of which the following is a specification.

This invention relates to auger-bits; and its object is to provide a bit of this character 10 which has an adjustable cutter, whereby the diameter of the bore may be of any desired size.

The device is more particularly designed as an improvement upon the bit described 15 and claimed in Patent No. 825,479, which was granted to me on July 10, 1906.

The object of the present invention is to simplify the present construction and to provide durable and compact means for 20 locking the adjustable cutter in desired position, said means being capable of easy manipulation.

With these and other objects in view the invention consists of certain novel features 25 of construction and combinations of parts, which will be hereinafter more fully described, and pointed out in the claims.

In the accompanying drawings is shown the preferred form of the invention.

30 In said drawings, Figure 1 is a perspective view of the auger-bit, a portion of the housing of the plunger being broken away. Fig. 2 is a longitudinal section through the bit, and Fig. 3 is a transverse section there- 35 through on line xx of Fig. 2.

Referring to the figures by characters of reference, 1 is the shank of a bit, the same having an enlarged head 2, substantially semicylindrical in form and terminating in a 40 cutting-head 3, from which extends a screw 4. Brazed upon or formed integral with the flat face of the head 2 is a housing 5, having a transverse passage 6 therethrough, which communicates with a longitudinal passage 7. The housing is preferably beveled toward the shank 1, as shown at 8, while that end of the housing adjacent the cutting-head 3 is reduced to form a base 9, in which is produced a transversely-extending dovetailed 45 groove 10. A cutting-blade 11 is slidably mounted on the base 9 and has a beveled cutting edge which overlaps the head 3, and the inner face of this cutting-blade is flat, so as to fit firmly upon the base 9. A dovetailed tongue 12 is formed upon the flat face of the 50

cutting-blade and is slidably mounted within the groove 10. An arm 13 extends at right angles from one end of the cutting-blade and has a rack 14 formed integral therewith and extending at right angles 60 therefrom, said rack being slidably mounted within the passage 6 and the toothed portion 15 thereof being beveled, as shown particularly in Figs. 1 and 2. This toothed portion is adapted to be engaged by the toothed 65 beveled end 16 of a plunger 17, which is slidably mounted in the passage 7 and has an integral hook 18 at its outer end, which engages a circular flange 19, formed upon an eccentric 20, rotatably mounted on a pivot 70 21, connected to the shank 1. An arm 22 extends from the eccentric, so as to enable it to be readily manipulated.

When it is desired to adjust this auger-bit so as to produce a bore of large diameter, the 75 arm 22 is swung so as to cause the eccentrically-arranged flange 19 to pull longitudinally on plunger 17 and withdraw it from engagement with the teeth 15. The rack 14 can then be slid longitudinally, so as to move 80 the cutting-blade laterally and bring the front or advancing edge thereof at a desired distance from the longitudinal center of the bit. When the desired adjustment has been secured, the eccentric is again partly rotated, 85 so as to force the plunger longitudinally into engagement with the rack, whereupon the parts will be securely locked in place. As the rack is beveled and as that end of the plunger engaging it is also beveled, it will be 90 understood that the end of the plunger constitutes a wedge, which not only engages the rack, but wedges between the housing and rack, so as to force the rack against the shank and hold it thereagainst. The eccentric will 95 be held in position after adjustment by reason of its frictional contact with the hook 18.

It will be seen that by constructing the bit in the manner described the parts are compactly arranged and cannot be forced out of position after an adjustment has once been effected. The cutting-blade is rigidly connected to the head of the bit and no oscillation thereof is permitted when the parts have once been secured.

The preferred form of the invention has been set forth in the foregoing description; but I do not limit myself thereto, as I am aware that modifications may be made therein without departing from the spirit or sacri- 110

ficing the advantages thereof, and I therefore reserve the right to make such changes as fairly fall within the scope of the claims.

What is claimed is—

- 5 1. In an auger-bit the combination with a shank having a head at one end thereof, and a housing upon the shank adjacent the head and having a transverse and a longitudinal passage; of a cutting-blade slidably mounted upon and engaging the shank adjacent the head, a rack integral with said blade and slidably mounted within the transverse passage, said rack having a beveled toothed portion, a plunger slidably mounted within the longitudinal passage and having a beveled toothed end constituting a wedge for engaging the rack, and means upon the shank for moving the end of the plunger into engagement with the rack and for wedging said end between the housing and rack.
- 10 2. In an auger-bit the combination with a shank having a head at one end thereof, and a housing upon the shank; of a cutting-blade extending transversely of the shank, an integral portion upon the blade and movable transversely within the housing, said portion having a beveled face, a plunger slidably mounted within the housing and having a beveled end constituting a wedge, and means for actuating the plunger to force this beveled end between the housing and the beveled face of said integral portion to bind said portion to the shank.
- 15 3. An auger-bit comprising a shank having a cutting-head, a housing adjacent the cut-

ting-head and having communicating transverse and longitudinal passages, one end of said housing being reduced and having a dovetailed groove, a cutting-blade slidably mounted on the reduced portion of the housing, a tongue thereon within and engaging the walls of the groove, a rack integral with the cutting-blade and slidably mounted within the transverse passage, a plunger in the longitudinal passage, an eccentric movably mounted on the shank for shifting the plunger into or out of engagement with the rack.

4. An auger-bit comprising a shank having a cutting-head, a housing adjacent the cutting-head and having communicating transverse and longitudinal passages, one end of said housing being reduced and having a dovetailed groove, a cutting-blade slidably mounted on the reduced portion of the housing, a tongue thereon within and engaging the walls of the groove, a rack integral with the cutting-blade and slidably mounted within the transverse passage, said rack having a beveled toothed portion, a plunger slidably mounted within the longitudinal passage and having a beveled toothed portion, and an eccentric upon the shank for moving the plunger into or out of engagement with the rack.

In testimony that I claim the foregoing as my own I have hereto affixed my signature in the presence of two witnesses.

JAMES THOMAS PARKER.
